UNITED STATES PATENT OFFICE.

ROBERT GRIFFIN, OF NEW YORK, N. Y.

DESIGN FOR WALL-PAPER.

40,819.

Specification for Design.

Patented Aug. 9, 1910.

Application filed June 10, 1910. Serial No. 566,270. Term of patent 3½ years.

To all whom it may concern:

Be it known that I, ROBERT GRIFFIN, a citizen of the United States, residing at New York, in the county and State of New York, have invented a new, original, and ornamental Design for Wall-Paper, of which the following is a specification, reference being had to the accompanying drawing, forming part thereof.

The figure shows a portion of a strip of wall paper bearing my new design.

I claim:

The ornamental design for wall paper, as shown.

ROBERT GRIFFIN.
